UNITED STATES PATENT OFFICE

STEPHEN H. TAYLOR, OF LUDLOW, KENTUCKY

WATER WHEEL

Application filed December 31, 1929. Serial No. 417,790.

This invention aims to provide a water wheel which will be efficient and simple in operation, the construction being such that the wheel will not get out of order, novel means being supplied for mounting the wheel and its shaft for rotation.

It is within the province of the disclosure to improve generally and to enhance the utility of devices of that sort to which the 10 present invention appertains.

With the above and other objects in view, which will appear as the description proceeds, the invention resides in the combination and arrangement of parts and in the 15 details of construction hereinafter described and claimed, it being understood that changes may be made in the precise embodiment of the invention herein disclosed, within the scope of what is claimed, without departing 20 from the spirit of the invention.

In the accompanying drawings:

Figure 1 shows in vertical longitudinal section, a device constructed in accordance with the invention, parts being in elevation;

25 Figure 2 is a cross section on the line 2—2 of Figure 1;

Figure 3 is a fragmental side elevation;

Figure 4 is a section taken through the water wheel and attendant parts;

30 Figure 5 is an elevation showing the water wheel, parts being broken away;

Figure 6 is a sectional view showing one of the pivots.

The numeral 1 indicates the floor of a vertical shaft, through which water can flow downwardly from a flume or other source of supply. The floor 1 has an opening 2. The floor 1 is supported on a channel beam 3. A frame 4 rests on the floor 1. The frame 4 is a composite structure.

40 The frame 4 comprises a bottom plate 5. Securing elements 6 connect the bottom plate 5 with the floor 1 and with the beam 3. The frame 4 comprises a top plate 7. The top plate 7 has a neck 8.

45 The neck 8 of the top plate 7 is supplied with a circumferential shoulder 9. The neck 8 has a chamber 11. There is a concaved recess 10 in the lower surface of the top plate 7.

The neck 8 has an opening 12 that communicates with the recess 10 and with the chamber 11. Securing devices 14 connect the top plate 7 with the bottom plate 5. Tubular spacers 15 are mounted on the securing devices 14, between the top plate 7 and the bottom plate 5.

55 A pedestal 16 is secured at 17 to the neck 8 of the top plate 7. In the lower end of the pedestal 16 there is a chamber 18. The 60 chamber 18 in the pedestal 16 communicates with the chamber 11 in the neck 8 of the top plate 7. There is a conical passage 19 in the pedestal 16. The lower end of the passage 19 communicates with the chamber 18.

65 The pedestal 16 has a cylindrical bore 20, provided with an enlargement 21 defining a shoulder 22. The bore 20 communicates at its lower end with the conical passage 19. The bore 20 communicates at its upper end 70 with a compartment 23 in the pedestal 16.

75 The pedestal 16 has a lateral opening 24 which communicates with the compartment 23. A closure 25 for the opening 24 is provided. The closure 25 is held on the pedestal 16 by securing elements 26. The pedestal 16 is provided with a cylindrical bore 27. The lower end of the bore 27 is in communication with the compartment 23. The upper end of the bore 27 is in communication with a conical passage 28 in the upper end of the pedestal 16.

80 A conical bearing 29 is mounted in the passage 28. The conical bearing 29 has external longitudinal slots 30. Retainers 31, such as 85 screws, are threaded into the pedestal 16 transversely thereof. The inner ends of the retainers 31 are received in the slots 30. The retainers 31 keep the bearing 29 from rotating; they do not, however, prevent the bearing 29 from sliding lengthwise in the passage 28.

90 The bearing 29 is shoved down and seated water-tight in the pedestal 16 by compression springs 32. The upper end of the spring 32 95 engages an abutment plate 34. The abutment plate 34 can slide vertically on studs 35 mounted at their lower ends in the pedestal 16. Nuts 36 are threaded on the studs 35. The nuts 36 are used to adjust the position of the 100

abutment plate 34 and the compressive effort of the spring 32.

A conical bearing 37 is mounted in the passage 19. The bearing 37 has external longitudinal slots 38. Retainers 39, such as screws, are threaded into the pedestal 16. The inner ends of the retainers 39 are received in the slots 38 of the bearing 37.

The retainers 39 hold the bearing 37 against rotation, but do not prevent the bearing from moving longitudinally.

The bearing 37 is shoved upwardly and seated in the passage 19 by a compression spring 40. The lower end of the compression spring 40 is engaged by an abutment plate 41. The abutment plate 41 slides on studs 42 mounted in the pedestal 16. Nuts 43 are threaded on the studs 42. The nuts 43 engage the abutment plate 41, to regulate the position of the abutment plate and to adjust the compressive effort of the spring 40.

The lower end of the bearing 37, the abutment plate 41, the spring 40, the studs 42, and the nuts 43 are located in the cooperating chambers 18 and 11.

A ball race 44 is mounted in the enlargement 21 of the bore 20 and rests on the shoulder 22. Balls 45 are located in the ball race 44. The numeral 46 marks a collar that turns within the circle defined by the balls 45. The collar 46 has a disk 47 that overlaps the ball race 44 and holds the balls 45 in place in the ball race.

The collar 46 is secured at 48 to a shaft 49. The shaft 49 is journaled in the bearing 29 and extends upwardly through the spring 32 and the abutment plate 34, the shaft extending downwardly, and being journaled in the bearing 37. The shaft 49 extends through the spring 40 and the plate 41, and is prolonged downwardly through the opening 12 in the top plate 7 of the frame 4.

The spring 40 cooperates with the bearing 37, and the spring 35 cooperates with the bearing 29, to take up wear and to keep the shaft 49 centered, lateral friction being taken care of by the collar 46 and the ball bearings 45-46. The lower end of the shaft 49 is maintained in proper position by a bearing mechanism which will now be described.

A base plate 50 rests on the beam 3. A sleeve 51 is supported on the base plate 50. The sleeve 51 has a tapered or conical passage 52. In the upper surface of the base plate 50, there is a seat 54. Balls 55 are mounted in the seat 54. The shaft 49 has a reduced lower end 56 defining a shoulder 57. The shoulder 57 rests on the balls 55. The reduced end 56 of the shaft 49 turns within the circle formed by the balls 55.

A conical bearing 58 is mounted in the passage 52. The bearing 58 has external longitudinal slots 59. Retainers 60, preferably screws, are mounted in the sleeve 51, transversely thereof. The inner ends of the re-

tainers 60 are received in the slots 59 of the bearing 58. The retainers 60 prevent the bearing 58 from rotating, but do not prevent it from moving downwardly. The bearing 58 is forced downwardly to a seat in the passage 52 by a strong compression spring 61. The upper end of the spring 61 is engaged with an abutment plate 62. The abutment plate 62 slides for adjustment on studs 63, the lower ends of which are mounted in the upper end of the sleeve 51. Nuts 64 are threaded on the studs 63, to adjust the position of the abutment plate 62, and the compressive effort of the spring 61. The shaft 49 is journaled in the bearing 58.

A water wheel is secured to the shaft 49, and is constructed as follows:

The water wheel comprises a cylindrical hub 65. A cap 66 rests on the hub 65. The cap 66 has a flat bottom, and has a convexed upper surface that fits closely but rotatably in the recess 6 of the top plate 7. The cap 66 and the hub 65 are secured to the shaft 49 by a key 67. The hub 65 is provided with an opening 68 receiving the sleeve 51 and attendant parts. The hub 65 carries external circumferentially inclined blades.

A means is provided for admitting water in a predetermined quantity upon the blades 69, and this means will now be described.

Vertical gates 70 are located around the water wheel. The gates 70 have stub shafts 71 at their upper and lower ends. The stub shafts 71 turn in the top plate 7 and in the bottom plate 5 of the frame 4. Connections 72 are mounted in the gates 70. The connections 72 are held in adjusted positions by nuts 73 threaded on the connections and located on each side of each gate 70. The outer ends of the connections 72 are connected by joints 74 with the lower ends of levers 75.

The levers 75 swing in vertical planes and are fulcrumed on brackets 76 which are secured to the top plate 7 of the frame 4. The upper ends of the levers 75 are pivotally connected with links 77. The links 77 can swing horizontally. The inner ends of the links 77 are pivotally connected at 79 with a rotor 80.

The rotor 80 is journaled on the neck 8 of the top plate 7, and is supported on the shoulder 9. Any suitable means may be provided for turning the rotor 80 for adjustment. If desired, the rotor 80 may have a lateral arm 81, a link 82 being pivoted at 83 to the arm.

In practical operation, the rotor 80 is turned through the instrumentality of the arm 81 and the link 82. The links 77 tilt the levers 75, and the adjustable connections 72 swing the gates 70 on the stub shafts 71, so as to open the gates more or less at the will of an operator, and to admit a governed amount of water on the blades 69 of the water wheel.

The water, having exerted its force on the blades 69, passes downwardly through the

opening 2 in the floor 1 of the shaft, it being understood that the water moves downwardly in a vertical shaft (not shown) whereof the floor 1 constitutes a part.

5 What is claimed is:

1. In a device of the class described, a frame comprising a top plate having a concaved recess, a water wheel including a convexed cap shaped to fit in the recess, a hub whereon the cap rests, circumferentially inclined blades carried by the hub, a shaft extending through the cap and into the hub, means for securing the shaft to the cap and to the hub, and a thrust bearing supporting the shaft, the hub having in its lower end an opening wherein the thrust bearing is received.

2. In a device of the class described, a frame, a water wheel within the frame, a shaft carrying the water wheel and extended out of the frame, pivotally mounted gates arranged in the frame, about the water wheel, connections mounted in the gates, means for adjusting the connections in the direction of 25 their length and transversely of the gates, substantially vertical levers fulcrumed intermediate their ends on the frame, joints forming an operative union between the lower ends of the levers and the connections, a member 30 mounted to rotate for adjustment about a vertical axis on the frame, and substantially horizontal links pivoted at their inner ends to the rotary member, and at their outer ends to the upper ends of the levers.

35 In testimony that I claim the foregoing as my own, I have hereto affixed my signature.

STEPHEN H. TAYLOR.
